UNITED STATES PATENT OFFICE

114,822

DESIGN FOR A STANDARD FOR A DENTAL UNIT OR THE LIKE

Edward L. Monnot, Canton, Ohio, assignor to
The Weber Dental Manufacturing Company,
Canton, Ohio, a corporation of Ohio

Application August 6, 1938, Serial No. 79,164

Term of patent 7 years

To all whom it may concern:

Be it known that I, Edward L. Monnot, a citizen of the United States, residing at Canton, in the county of Stark and State of Ohio, have invented a new, original, and ornamental Design for a Standard for a Dental Unit or the like, of which the following is a specification, reference being had to the accompanying drawing, forming part thereof.

Figure 1 is a front perspective view of a standard for a dental unit or the like, showing my new design, the dominant features of the design being shown in full lines;

Fig. 2, another perspective view thereof looking towards one front corner of the standard, the dominant features of the design being shown in full lines; and

Fig. 3, a transverse sectional view on a slightly enlarged scale, substantially on the line 3—3, of Fig. 1, showing the contour of the standard.

I claim:

The ornamental design for a standard for a dental unit or the like, as shown and described.

EDWARD L. MONNOT.
